US00D648186S

(12) **United States Design Patent**
Pourian et al.

(10) **Patent No.:** **US D648,186 S**
(b4) **Date of Patent:** **** Nov. 8, 2011**

(54) **DISPENSER**

(75) Inventors: **Neema Pourian**, Skokie, IL (US); **Sa Xiao Marty**, Chicago, IL (US); **Yael Karni**, Chicago, IL (US)

(73) Assignee: **Wm. Wrigley Jr. Company**, Chicago, IL (US)

(**) Term: **14 Years**

(21) Appl. No.: **29/388,442**

(22) Filed: **Mar. 29, 2011**
